(57) **CLAIM**

We claim the ornamental design for a food cooking appliance, as shown and described.

DESCRIPTION

FIG. 1 is a front right perspective view of a food cooking appliance;

FIG. 2 is a front elevational view thereof;

FIG. 3 is a top plan view thereof;

FIG. 4 is a right side elevational view thereof, the opposite side being a mirror image of that shown;

FIG. 5 is a rear elevational view thereof;

FIG. 6 is a front right perspective view of another embodiment of the food cooking appliance;

FIG. 7 is a front elevational view thereof;

FIG. 8 is a top plan view thereof;

FIG. 9 is a right side elevational view thereof, the opposite side being a mirror image of that shown; and,

FIG. 10 is a rear elevational view thereof.

The broken lines shown in FIGS. 1, 2, 4, 6, 7, and 9 are for illustrative purposes only and form no part of the claimed design.
